ABSTRACT

A method for decreasing the reproductive function of mammals by administering a pharmacologically effective amount of a certain organosilicon compound. As a means of illustration, one can orally or parenterally administer an effective amount in the range of from 100 mg. to 5,000 mg. per kilogram of body weight (either as a single dose or as a daily dosage over a period of time) of an organosilicon compound of the formula

thereby rendering the subject (either a male or female mammal) sterile.

6 Claims, No Drawings

METHOD FOR DECREASING THE REPRODUCTIVE FUNCTION OF MAMMALS

This application is a continuation-in-part of U.S. application, Ser. No. 837,922, filed June 30, 1969; now U.S. Pat. No. 3,830,912 which in turn is a continuation-in-part of U.S. application Ser. No. 741,336, filed July 1, 1968; now abandoned.

This invention relates to a method for altering the reproductive function of mammals.

We have discovered that the administration of a pharmacologically effective amount of a certain organosilicon compound can alter the genital function (which includes reproductive capacity) of mammals. More precisely, a male mammal so treated exhibits depressant effects. For example, the sex accessory organs of the male (seminal vesicle, prostate) can be reduced in function and/or size and, with sufficient dosage, the male can also be rendered sterile as a result of depression of testes function. A female mammal so treated exhibits a decrease of fertility, i.e., the female mammal's capability to conceive is inhibited with larger doses such that the female may be rendered sterile or abort if pregnant.

The principal object of this invention is to provide a therapeutically effective organosilicon compound which can render a male or female mammal sterile. Another principal object of this invention is to provide a method of administering an organosilicon compound which can be useful in the treatment of prostatic hypertrophy. It is still another object of this invention to provide a method of administering a certain organosilicon compound to females whereby the female's capability to conceive or support and carry a living fetus through a normal pregnancy to a healthy birth can be inhibited. These and other attendant objects will become readily apparent from the detailed description which follows.

This invention relates to a method for decreasing the reproductive function of mammals which comprises administering an effective amount in the range of from 100 mg. to 5,000 mg./kg. of an organosilicon compound of the formula

The organosilicon compound can be named as mono-phenylseptamethylcyclotetrasiloxane.

The organosilicon compound noted herein can be readily prepared by well known techniques described in the literature, e.g., by the cohydrolysis of chlorosilanes or by a suitable Grignard reaction.

The process of the present invention is operative on any mammal, e.g., rodents such as mice, rabbits and rats; domestic animals such as cats, swine, dogs, cattle, horses, and sheep; animals wild in nature such as deer, fox, wolves and lynx; and primates such as monkeys and man.

One can administer the organosilicon compound in any pharmacologically acceptable manner. They can be orally administered, parenterally administered or, in

certain species, topically administered. The parenteral mode of administration would, of course, include subcutaneous administration, intramuscular administration and the like.

It is of importance to note that the organosilicon compound described herein can be administered either in pure form or combination with a pharmaceutically acceptable carrier or diluent. Suitable carriers include sesame oil, corn oil, mineral oil and other well known fat soluble carriers commonly employed in numerous pharmaceutical preparations.

As mentioned herein, the dose range of the organosilicon compound is in a pharmacologically effective amount. A dose range of from about 100 mg. to about 5,000 mg. per kilogram of body weight has been found to be suitable; however, the precise dosage is ultimately dependent upon the mammal, the vehicle used, the route of administration, and the specific effects one wishes to achieve. The organosilicon compound may be administered as a single dose or it may be administered in daily dosage over varying periods of time, e.g., from about 7 to about 30 days or more.

The time required to achieve the desired effect is also variable, ranging anywhere from days to weeks or months, depending upon various factors, e.g., the species of mammal, dosage, route of administration, and the specific effect one wishes to achieve.

The particular alteration of the reproductive function which has been observed after administering the compound of the present invention to male mammals is a decrease in sex accessory organ function (decreased seminal fluid) and size (decreased seminal vesicle) with smaller doses of the compound and a decrease in prostatic or testicular function (decreased sperm count) or size with larger doses.

In view of the above, the method of this invention can be useful for decreasing the size of male sex accessory organs. In this regard, sex accessory organs are more sensitive than the testes to the organosilicon compound so that it is possible to decrease prostatic function and size without producing a significant effect on testicular size.

Furthermore, the method of this invention can be particularly useful for the treatment of prostatic hypertrophy. For example, by orally administering the compound of the formula

at a daily (seven daily doses) dosage level of 100 mg. per kg. of body weight, it has been found that the prostate is significantly reduced in size.

If a high dosage level is maintained over a fairly long period of time in females prior to, during and/or following copulation, the anticipated embryo may fail to form or it may be resorbed by the female mammal.

It is also possible to prevent pregnancy (contraception) or abort pregnancy in female mammals because of an estrogenic depressant activity of certain of the organosilicon compound described herein.

In all of the foregoing cases, the pharmacological actions are reversible.

The following examples are illustrative only and should not be construed as limiting the invention which is properly delineated in the appended claims.

EXAMPLE 1

This example illustrates depressant activity of a certain organosilicon compound in the male rat.

A group of male rats (Sprague - Dawley strain) were orally dosed via gastric intubation with an organosilicon compound of the formula

The animals were administered 100 mg./kg. of body weight of the compound for a period of seven days with autopsy on day eight. Final body weights were determined in the fasted state just prior to sacrifice. Table I illustrates the depressant activity in the form of decreased seminal fluid, seminal vesicle and prostate weights.

EXAMPLE 2

This example illustrates the estrogen-like activity of the organosilicon compound in the immature female rat.

for 3 days with autopsy of day four. The percent increase in uterine weight was determined between the control (sesame oil) and the treated animals. Table II illustrates estrogen-like activity in the immature female rat based upon percent increase in uterine weight.

TABLE II

Estrogen-Like Activity of a Certain Organosilicon Compound in the Immature Female Rat						
	Group	Dose mg./kg.	n	Mean Uterine Weight (gm.) 100 gm. final Body Weight	Uterine Weight % Increase	
10	Control (sesame oil)	—	6	61.64	—	
15	(CH ₃) ₂ Si-O-Si-(CH ₃) ₂ *					
20	(CH ₃) ₂ Si-O-Si-C ₆ H ₅	50	6	117.18	90**	
(CH ₃) ₂ Si-O-Si-(CH ₃) ₂ *						
(CH ₃) ₂ Si-O-Si-C ₆ H ₅	200	6	176.93	187**		

*daily oral dosing for 3 days with autopsy on day 4.

**p .01 compared to control.

*ratio equals organ or fluid weight (grams)/final body weight (grams.)

**daily oral dosing of 100 mg./kg. of body weight for 7 days with autopsy on day 8.

***p .001 compared to control.

An immature female Wistar rat was orally administered (via gastric intubation) either 50 mg./kg. of body weight or 200 mg./kg. of body weight of an organosilicon compound of the formula

50

EXAMPLE 3

This example illustrates the anti-estrogen activity of the organosilicon compound in the immature female rat. Organosilicon compound induced depression of uterine weight stimulated by estradiol benzoate was used as a measure of anti-estrogen activity. Table III illustrates the results obtained.

TABLE III

Anti-Estrogen Activity of The Organosilicon Compound in the Immature Female Rat				
Group	Organosilicon Dose mg./kg.	n	Mean Uterine Weight (grams)/100 grams Final Body Weight	
(A) Control (sesame oil)	—	6	61.64	
(B) Estradiol benzoate				

TABLE III-continued

Anti-Estrogen Activity of The Organosilicon Compound in the Immature Female Rat			
Group	Organosilicon Dose mg./kg.	n	Mean Uterine Weight (grams)/100 grams Final Body Weight
(1.0 mg. total dose)	—	6	197.06
(C)	5.0	6	194.74
(D)	20.0	6	1169.33

*Compound administered orally for three days with autopsy on day 4. Estradiol benzoate given subcutaneously in groups B, C and D.

EXAMPLE 4

Table IV illustrates the antifertility activity noted above.

TABLE IV

Antifertility Activity of The Organosilicon Compound Administered Orally for Seven Days Prior to Mating to Proven Breeder Female Mice					
	First Mating	Number Pregnant Total Number	Mean Number Pups/Female	Second Mating	Number Pregnant Total Number
(A) Control - No Treatment		3/3	9.33		3/3
(B) Sesame Oil		3/3	10.33		3/3
(C)		3/3	10.33		1/3
(D)		3/3	10.67		1/3

This example illustrates the antifertility activity of the organosilicon compound administered orally for seven days prior to mating to proven breeder female mice.

A group of untreated female mice (Cox strain) were mated with a group of untreated male mice and animals which became pregnant and delivered an average normal litter in this first mating. Mice from this group were then selected as proven breeders for a second mating. These mice in the second mating were orally dosed (via gastric intubation) with either nothing, sesame oil, or two different doses (50 mg./kg. of body weight or 200 mg./kg. of body weight) of the organosilicon compound of the formula

That which is claimed is:
1. A method for decreasing the reproductive function of mammals which comprises administering to a mammal an effective amount in the range of from 5 mg. to 200 mg./kg. of mammal body weight of an organosilicon compound of the formula

55

60

65

66

2. The method as recited in claim 1 in which the depression of the reproductive function is the depression of the weight of male sex accessory glands.
3. The method as recited in claim 1 in which the depression of reproductive function is female antifertility.
4. The method as recited in claim 1 in which the organosilicon compound is administered orally.

5. The method as recited in claim 1 in which the organosilicon compound is administered in combination with a pharmaceutically acceptable carrier.

6. The method as recited in claim 5 in which the carrier is sesame oil.
